Primary Examiner — Samantha Wood

(74) Attorney, Agent, or Firm — Merchant & Gould P.C.

(57) **CLAIM**

The ornamental design for a shower handle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a shower handle showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The even and uneven length broken lines depicting the shower trim plate form no part of the claimed design.

**1 Claim, 6 Drawing Sheets
(6 of 6 Drawing Sheet(s) Filed in Color)**
